UNITED STATES PATENT OFFICE.

GEORGE LEICH, OF ROCKVILLE CENTER, NEW YORK.

BURNER.

Application filed August 6, 1924. Serial No. 730,351.

To all whom it may concern:

Be it known that I, GEORGE LEICH, a citizen of the United States, and residing at Rockville Center, L. I., in the county of 5 Nassau and State of New York, have invented certain new and useful Improvements in Burners, of which the following is a specification, such as will enable those skilled in the art to which it appertains to 10 make and use the same.

This invention relates to burners and particularly to devices for use in connection with or as a part of heating apparatus of various kinds and classes, such for example

15 as steam boilers, hot water boilers, hot air furnaces and the like; and the object of the invention is to provide a device or apparatus of the class specified which is so constructed as to permit of the ready adaptation there- 20 of in connection with heating apparatus commonly known and now in use, without material change or alterations in the structure of the heating apparatus; a further object being to provide means for feeding the 25 fuel to the burner device by the velocity of flow of steam around and by the fuel oil nozzle of the apparatus; a further object being to so circulate the fuel oil and steam through the burner device as to form of said

30 elements a desirable gaseous mixture which when ignited, produces a flame having the highest possible degree of heat; a further object being to provide a burner composed of a plurality of substantially similar elements coupled together to form the device, and with means for supporting a steam boiler within said elements, said elements being preferably in the form of tubular members and means for placing the separate tubular

35 members in communication; a further object being to provide means independent of the burner nozzles for initially heating the water in said boiler and for generating steam therein; a further object being to provide 40 means for maintaining a fixed level of water in the boiler and for automatically replenishing the supply of water thereto; a still further object being to provide means for automatically and positively controlling the supply of fuel to the burner whereby the over- 45 flow or flushing of the fuel oil is obviated; and with these and other objects in view, the invention consists in an apparatus of

50 the class and for the purpose specified, which

is simple in construction, efficient in use, and 55 which is constructed as hereinafter described and claimed.

The invention is fully disclosed in the following specification, of which the accompanying drawing forms a part, in which the 60 separate parts of my improvement are designated by suitable reference characters in each of the views, and in which:—

Fig. 1 is a diagrammatic view showing my improved burner mounted in the fire box 65 of a furnace, and illustrating the several parts of the apparatus employed in connection with the burner.

Fig. 2 is a longitudinal sectional view through the burner shown in Fig. 1 with 70 parts of the construction omitted and on an enlarged scale.

Fig. 3 is a sectional plan view of the burner proper, parts of the construction being 75 broken away and in section.

Fig. 4 is a sectional detail view of a part of the construction shown in Figs. 1 and 2 of the drawing.

Fig. 5 is a transverse sectional view 80 through the burner device, adjacent one end portion thereof.

Fig. 6 is an end view of the burner, showing one end portion thereof.

Fig. 7 is a view similar to Fig. 6 but showing the other end portion of the burner. 85

Fig. 8 is a sectional detail view of a part of the construction shown in Fig. 1; and,

Fig. 9 is a sectional detail view of a fuel and steam nozzle which I employ.

In Fig. 1 of the drawing, I have indicated 90 at 10 a furnace of a steam system for the purpose of illustrating one use of my invention, and in said figure 11 represents the fire box, 12 the grate, 13 the fire box door, 14 the draft door and 15 the clinker 95 door opening which in the use of my improved burner is closed by a wall member 16 through which certain pipes and the like are adapted to pass.

It will be noted that my improved burner 17 may be mounted upon the grate 12 of the furnace as indicated in Fig. 1 of the drawing, or the burner may be supported in the furnace in any desired manner. In Fig. 1, I have also indicated at 18 an oil tank, 19 a shut-off valve, 20 a feed control valve. 105 22 represents what is known as a whistle valve controlled by a diaphragm valve 23,

the valve 22 being mounted in the oil feed pipe 24 through the tank 18. 25 represents a water feeder placed in communication with a suitable source of water supply 5 through a pipe 26 having a valve 27 therein, and at 28 I have indicated a gas feed pipe from a suitable source of gas supply, in which is a controlling valve 29, and adjustable air regulator 30.

- 10 The mechanisms above described are placed in communication with the burner 17 in the manner hereinafter set out, and in the accompanying drawing, the burner is constructed of a series of substantially yoke-shaped tubular sections 31, all of which are practically of the same general construction or consist of the top V-shaped tubular cross head 32, depending side tubular members and inwardly directed tubular members 15 terminating in circular coupling heads 33 which are enlarged laterally as clearly seen in Fig. 3 of the drawing and these coupling heads are adapted to be coupled together by two types of tubular unions or coupling 20 members 34 and 35, the unions 34 being open throughout while the unions 35 have partition walls transversely thereof forming 25 closures for sealing the communication between adjacent sections 31.
- 30 In the construction shown, seven of the sections 31 are employed, and one of the end sections, the end section to the right as shown in Figs. 1, 2 and 3 of the drawing, and one of the inwardly directed end portions 35 thereof, the end portion to the left as viewed in Fig. 7 of the drawing, is threaded to receive a pipe 36, while the other end of said section is closed by a plug 37. The other end section, namely that to the left 40 in the above named figures or the end member to the left thereof as viewed in Fig. 6 of the drawing, is threaded to receive a pipe 38, while the other end is closed by a plug 39. The sections 31 are coupled together by 45 the couplings or unions 34 and 35 which are pressed in position forming substantially a unitary structure of the sections employed. To one end of said sections is secured a plate 40 which is of the general form indicated in 50 Fig. 7 of the drawing, and to the other end is secured a plate 41 of the general form shown in Fig. 6 of the drawing. Three burner tubes 42 are mounted longitudinally of the burner at a predetermined distance 55 beneath the sections 31, said tubes passing through the plate 41 and having a bearing in the plate 40, and two gas burner tubes 43 are passed through the plate 40 and have bearings in the plate 41, said last named tubes being positioned above the central burner tube 42 and within the sections 31 centrally thereof.
- 55 Formed within and around the sections 31 is a combustion chamber which opens outwardly through the separate sections 31 at

the top, bottom and sides thereof, and centrally of said chamber and said sections is a steam boiler 44 which extends longitudinally of the burner and which, in the construction shown, is of the cross sectional form indicated in Fig. 5 of the drawing, said boiler being supported by cross members 45 coupled with standards 46 forming part of the sections 31 as clearly shown in Figs. 5 and 6 and 7 of the drawing, the boiler 44 being provided at the top of the front end portion thereof with an upwardly and outwardly directed box-shaped extension 47 forming a steam chest 48, and an inwardly and downwardly tapered baffle wall 49 extends into the boiler adjacent the communication between it and the steam chest 48 and forms a contracted discharge 50 between the boiler and steam chest. The baffle wall prevents water from coming into the steam chest when boiling in the generation of the steam. A pipe 51 is coupled with the lower end portion of the boiler 44 and passes through the plate 40 and is in communication with the water feed device 25. Another pipe 52 is in communication with the steam chest 48 and with the top of the feed device 25, said pipe being also directed to the diaphragm regulating valve 23 through a branch 52^a of the pipe 52 as shown in Fig. 1 of the drawing. Another pipe 53 is in communication with the steam chest 48 and is coupled with a fuel feeding device 54 shown in Figs. 1, 3 and 7 and in detail in Fig. 9 of the drawing.

The fuel feeding device is mounted in connection with the pipe 36 and has a discharge port 55 opening into said pipe 36, and mounted in the device 54 is an adjustable nozzle 56 retained in predetermined positions of adjustment by a lock nut 57, said nozzle comprising a large upper chamber 58 with which the oil feed pipe 24 from the valve 22 communicates, and a contracted discharge port 59 in the contracted end portion 60 of the nozzle 56, said end portion 60 extending into the nozzle discharge port 55 of the device 54. Within the device 54 around the nozzle 56 is a chamber 61 into which steam is adapted to pass from the pipe 53, which communicates with said chamber, see Fig. 9, and the velocity of steam flow around the contracted end 60 of the nozzle 56 will control the feed of oil into the pipe 36 through the discharge port 59 of the nozzle 56.

The water feeding device 25 for supplying water, automatically to the boiler 44, to maintain a fixed level therein is shown and described herein to clearly illustrate the complete apparatus, but this water feeding device in itself forms the subject of and is claimed in a companion application filed August 6, 1924, Serial No. 730,350. For convenience, the device 25 is mounted and

- supported on the gas feed pipe 28 and as shown said device comprises a dome-shaped casing 62 closed at its upper end and the lower end of which is open and adapted 5 to be closed by a cap 63. Mounted in connection with the cap 63 is a pivot bar 64 in connection with which a lever 65 is pivoted, one end of said lever being pivoted to a float 66 and a link 67 is pivoted to the 10 other end of said lever, said link being pivoted to the long arm of a lever 68 pivoted to a post 69 mounted on the cap 63, and the short arm 70 of the lever 68 is adapted to operate in connection with a pin 71 15 for moving a needle valve 72 into inoperative position. The needle valve 72 is movably mounted in a plug member 73 coupled with the cap 63, the needle valve being tapered at a predetermined point to operate in 20 connection with a tapered seat 74 to control the supply of water into the casing 62 from the water supply pipe 26 by the passage of said water through the by-pass port or 25 passage 75 in the plug 73 around the needle valve 72, when unseated, and into said casing through ports 76 as clearly shown in Fig. 4 of the drawing, it being understood that sufficient clearance is allowed around said needle valve to permit the passage of 30 water into the casing 62 when said valve is unseated, this clearance being very slight however.
- The water feeding device, it will be apparent, operates to automatically maintain 35 a fixed level in the steam boiler 44 as is diagrammatically shown in Fig. 2 of the drawing. When the water level drops in the casing 62, the float 66 will drop thus operating the levers 65 and 68 to depress 40 the pin 71 and unseat the needle valve 72, and when the proper level has been reached the needle valve 72 will be reseated by the pressure of water, especially in that the end portion of the needle valve is subject to 45 the direct water pressure, and the by-pass 75 functioning only to relieve or partially equalize the pressures to eliminate the use of a large float for actuating the needle valve against the prevailing water pressure.
- 50 It will be noted that the gas supply pipe 28 is coupled with a substantially T-shaped body 77 forming part of the plate 40 of the burner and the gas burner pipes 43 are in communication with the end portions of the 55 member 77. The gas and air mixture in the pipe 28 is discharged through the burner tubes 43 substantially as is diagrammatically illustrated in Fig. 5 of the drawing, or in directions at an angle to the vertical plane 60 of the burner to direct the flame from said burner tubes 43 against the boiler, and the tubular sections 31 adjacent the boiler. It will be understood that water has been placed in the boiler, and in the operation 65 of the burner tubes 43, the water in the boiler will be heated, in a matter of a few minutes, to a point where steam will be generated and this steam will be discharged into the steam chest 48 and will pass through the pipes 52 and 53, the communication of the pipe 52 with the water feeder serving to equalize the pressure on the body of water therein, and in the boiler, and the passage of the steam from the pipe 52^a to a diaphragm control 23 will operate 70 to automatically actuate the whistle valve 22 to place the tank 18 in communication with the fuel feeding device 54, it being understood that the valves 19 and 20 are in open and adjusted positions. The steam 75 in the steam chest 48 also passes to the chamber 61 of the device 54 through the pipe 53, and the velocity of steam flow around the nozzle 56 or the contracted end portion 60 thereof will control and regulate the feed 80 of fuel from the tank 18 into and through the tubular sections 31.
- At this point, it may be stated that while I have shown in full lines in Fig. 1 of the drawing, a substantial gravity feed to the fuel feeding device 54 from the tank 18, the fuel may be drawn by the vacuum created in the steam velocity flow to raise fuel from a tank at a lower level as indicated in dotted lines in said figure. Regardless of the 85 system employed for supplying the fuel, the fuel in comparatively small proportions, is mixed or mingled with the steam discharge into the pipe 36, and this mixture passes into the first section of the burner at the 90 left, see Fig. 7, through said section and into the adjacent section at the right when viewing the sections as in Fig. 7, thus through the second section and into the third section at the left, and so on until the same has been 95 discharged from the last section into the pipe 38, see Fig. 6 of the drawing. The pipe 38 is directed upwardly and then downwardly and is coupled with a three-way manifold 78 through a T-shaped coupling 100 105 79, see Fig. 2 of the drawing, and in said pipe and coupling is placed a nozzle 80 which is designed to increase the velocity flow at or within the T-shaped coupling 79 110 which has a downwardly directed elbow 81 115 opening to atmosphere, whereby air may be entrained into and mingled with the gaseous substance discharged into the manifold 78 through the nozzle 80, and the gas thus formed passes from the manifold 78 into 120 and through the burner tubes 42 and is discharged through nozzles or discharge ports spaced longitudinally thereof, and the arrangement is diagrammatically illustrated in Fig. 5 of the drawing, and is such as to 125 direct the flame from the burner tubes 42 onto the sections 31 as well as onto the boiler 44. It will be understood, when sufficient steam has been generated by the gas burner tubes 43, the gas supply may be shut 130

off through the valve 29 and the steam may continue to be generated by the action of the burner tubes 42 only.

The passage of the steam and fuel oil mixture into and through the tubular sections 31 which are heated to a high degree of heat, acts upon said elements to produce thereof a gas which I find to be most suitable and convenient for burners of the class under consideration. As a matter of fact the gas discharged from the burner tubes 42 produces the highest possible degree of heat with a minimum fuel consumption. I have also found that no carbon deposits or scales collect upon the several parts of the burner proper, and the burner will operate efficiently at a nominal cost without any care or attention. However, in the event that the burner tubes 42 or the flame thereof, should go out through any cause whatever and the steam cease to be generated, the diaphragm control valve 23 will operate to automatically shut off the supply of fuel to prevent the flooding or flushing of the burner tubes, especially if a gravity feed is employed, and in Fig. 8 of the drawing, I have illustrated a detail view of the valves 22 and 23 to illustrate that the diaphragm 23^a of the valve 23 operates upon a rod 23^b, which extends into the valve 22 and is adapted to operate the valve element 22^a thereof, the diaphragm 23^a being actuated by the steam pressure to which it is subjected. The valve 20 employed in the feed pipe 24 is used to control the amount of oil supplied to the burner, and by means of this valve the degree of heat desired in the use of my improved burner may be regulated.

In Fig. 1 of the accompanying drawings, the pipes 24, 28, 51 and 52 are passed through the walls 16 employed for closing the clinker door opening, but I am not necessarily limited to this specific construction as the pipes may be passed into a furnace or other heating element in any desired manner, and the burner may be mounted within the furnace in any way, or as hereinbefore stated, the furnace may be constructed to adapt the burner primarily thereto, and while I have shown certain details of construction for carrying my improved apparatus into effect and have shown a specific number of sections 31 in the burner proper and other structural details, it will be understood that I am not necessarily limited in these respects, and various changes in and modifications of the construction herein shown and described may be made within the scope of the appended claims without departing from the spirit of my invention or sacrificing its advantages.

Having fully described my invention, what I claim as new and desire to secure by Letters-Patent, is:—

65 1. An apparatus of the class described

comprising a burner unit composed of a plurality of intercommunicating passages, means in said unit whereby steam may be generated, means for initially heating said first named means to generate steam, means for utilizing the steam so generated to control the supply of fuel to the burner, means for circulating the steam and fuel through the passages of the burner to form thereof a combustible gas and for directing said gas to the discharge tubes of the burner unit, means whereby the burner unit may, when in operation, be utilized to generate steam in said first named means, and means for supplying air to the gas, prior to its admission into the tubes of the burner unit.

2. An apparatus of the class described comprising a burner unit composed of a plurality of intercommunicating passages, means in said unit whereby steam may be generated, means for initially heating said first named means to generate steam, means for utilizing the steam so generated to control the supply of fuel to the burner, means for circulating the steam and fuel through the passages of the burner to form thereof a combustible gas and for directing said gas to the discharge tubes of the burner unit, means whereby the burner unit may, when in operation, be utilized to generate steam in said first named means, means for supplying air to the gas, prior to its admission into the tubes of the burner unit, and means for automatically controlling the supply of water to the first named means.

3. An apparatus of the class described comprising a burner unit composed of a plurality of intercommunicating passages, means in said unit whereby steam may be generated, means for initially heating said first named means to generate steam, means for utilizing the steam so generated to control the supply of fuel to the burner, means for circulating the steam and fuel through the passages of the burner to form thereof a combustible gas and for directing said gas to the discharge tubes of the burner unit, means whereby the burner unit may, when in operation, be utilized to generate steam in said first named means, means for supplying air to the gas, prior to its admission into the tubes of the burner unit, and means for automatically controlling the supply of water to the first named means, and for maintaining a fixed water level therein.

4. An apparatus of the class described comprising a burner unit composed of a plurality of intercommunicating passages, means in said unit whereby steam may be generated, means for initially heating said first named means to generate steam, means for utilizing the steam so generated to control the supply of fuel to the burner, means

- for circulating the steam and fuel through the passages of the burner to form thereof a combustible gas and for directing said gas to the discharge tubes of the burner unit,
- 6 means whereby the burner unit may, when in operation, be utilized to generate steam in said first named means, means for supplying air to the gas, prior to its admission into the tubes of the burner unit,
- 10 means for automatically controlling the supply of water to the first named means and for maintaining a fixed water level therein, and means in communication with said first named means for automatically controlling
- 15 the supply of fuel to the burner unit.
5. An apparatus of the class described comprising a burner unit composed of a plurality of intercommunicating passages, means in said unit whereby steam may be generated, means for initially heating said first named means to generate steam, means for utilizing the steam so generated to control the supply of fuel to the burner, means for circulating the steam and fuel through
- 20 25 30 35 40 45 50 55 60 65 70 75 80 85 90 95 100 105 110 115 120 125 130
- the passages of the burner to form thereof a combustible gas and for directing said gas to the discharge tubes of the burner unit, means whereby the burner unit may, when in operation, be utilized to generate steam in said first named means, means for supplying air to the gas, prior to its admission into the tubes of the burner unit, means for automatically controlling the supply of water to the first named means and for maintaining a fixed water level therein, means in communication with said first named means for automatically controlling the supply of fuel to the burner unit, and means for controlling the volume of the fuel supply.
6. An apparatus of the class described comprising a burner unit, means in said unit whereby steam may be generated, means for initially heating said first named means to generate steam, means for utilizing the steam so generated to control the supply of fuel to the burner, means for circulating the steam and fuel through the burner to form thereof a combustible gas and for directing said gas to the discharge tubes of the burner unit, means whereby the burner unit may, when in operation, be utilized to generate steam in said first named means, means for supplying air to the gas prior to its admission into the tubes of the burner unit, means for automatically controlling the supply of water to the first named means and for maintaining a fixed water level therein, means for controlling the volume of the fuel supply, and an adjustable fuel nozzle constituting part of said fuel supply means.
7. An apparatus of the class described comprising a burner unit, means in said unit whereby steam may be generated, means for initially heating said first named means to generate steam, means for utilizing the
- steam so generated to control the supply of fuel to the burner, means for circulating the steam and fuel through the burner to form thereof a combustible gas and for directing said gas to the discharge tubes of the burner unit, means whereby the burner unit may, when in operation, be utilized to generate steam in said first named means, means for supplying air to the gas prior to its admission into the tubes of the burner unit, means for automatically controlling the supply of water to the first named means and for maintaining a fixed water level therein, means for controlling the volume of the fuel supply, and an adjustable fuel nozzle constituting part of said fuel supply means,
8. An apparatus of the class described comprising a burner unit comprising a plurality of intercommunicating tubular sections, a fuel nozzle in communication with the inlet end of said tubular sections, a fuel supply tank in communication with said nozzle, a steam boiler constituting part of said burner unit and located within said tubular sections, means for passing steam generated by said boiler around said nozzle to control the feed of oil to said burner unit, and means whereby the steam and oil may be circulated through the tubular section of the burner unit to form thereof a gas, which is directed to the burner tubes of said unit.
9. An apparatus of the class described comprising a burner unit comprising a plurality of intercommunicating tubular sections, a fuel nozzle in communication with the inlet end of said tubular sections, a fuel supply tank in communication with said nozzle, a steam boiler constituting part of said burner unit and located within said tubular sections, means for passing steam generated by said boiler around said nozzle to control the feed of oil to said burner unit, means whereby the steam and oil may be circulated through the tubular sections of the burner unit to form thereof a gas, which is directed to the burner tubes of said unit, and means whereby air may be mingled with said gas prior to its passage into said burner tubes.
10. An apparatus of the class described comprising a burner unit comprising a plurality of intercommunicating tubular sections, a fuel nozzle in communication with the inlet end of said tubular sections, a fuel supply tank in communication with said nozzle, a steam boiler constituting part of said burner unit and located within said tubular sections, means for passing steam generated by said boiler around said nozzle to control the feed of oil to said burner unit, means whereby the steam and oil may be circulated through the tubular sections of the burner unit to form thereof a gas, which is

directed to the burner tubes of said unit, means whereby air may be mingled with said gas prior to its passage into said burner tubes, and means in communication with 5 said boiler for automatically controlling the supply of oil to said nozzle.

11. An apparatus of the class described comprising a burner unit comprising a plurality of intercommunicating tubular sections, a fuel nozzle in communication with the inlet end of said tubular sections, a fuel supply tank in communication with said nozzle, a steam boiler constituting part of said burner unit and located within said 10 tubular sections, means for passing steam generated by said boiler around said nozzle to control the feed of oil to said burner unit, means whereby the steam and oil may be circulated through the tubular sections of 15 the burner unit to form thereof a gas, which is directed to the burner tubes of said unit, means whereby air may be mingled with said gas prior to its passage into said burner tubes, means in communication with said 20 boiler for automatically controlling the supply of oil to said nozzle, and other means in communication with said boiler for controlling the supply of water thereto and for maintaining a predetermined water level 25 therein.

12. An apparatus of the class described comprising a burner unit comprising a plurality of intercommunicating tubular sections, a fuel nozzle in communication with the inlet end of said tubular sections, a fuel supply tank in communication with said nozzle, a steam boiler constituting part of said burner unit, means for passing steam generated by said boiler around said nozzle 30 to control the feed of oil to said burner unit, means whereby the steam and oil may be circulated through the tubular sections of the burner unit to form thereof a gas, which is directed to the burner tubes of said unit, 35 means whereby air may be mingled with said gas prior to its passage into said burner tubes, means in communication with said boiler for automatically controlling the supply of oil to said nozzle, other means in communication with said boiler for controlling the supply of water thereto and for maintaining a predetermined water level 40 therein, and means for regulating the volume of fuel supply to said nozzle.

13. An apparatus of the class described comprising a burner unit comprising a plurality of intercommunicating tubular sections, a fuel nozzle in communication with the inlet end of said tubular sections, a fuel supply tank in communication with said nozzle, a steam boiler constituting part of said burner unit and located within said tubular sections, means for passing steam generated by said boiler around said nozzle 45 to control the feed of oil to said burner

unit, means whereby the steam and oil may be circulated through the tubular sections of the burner unit to form thereof a gas, which is directed to the burner tubes of said unit, means whereby air may be mingled 70 with said gas prior to its passage into said burner tubes, means in communication with said boiler for automatically controlling the supply of oil to said nozzle, other means in communication with said boiler for controlling the supply of water thereto and for maintaining a predetermined water level therein, means for regulating the volume of fuel supply to said nozzle, and means independent of the tubes of the burner 75 unit for initially heating said steam generator.

14. A burner of the class described comprising a plurality of tubular sections in communication one with the other, burner tubes in juxtaposition to and beneath said sections and in communication therewith, means for passing steam and fuel oil into and through the sections of said burner to form thereof a combustible gas and for 80 directing said gas to said burner tubes, means for mingling air with the gas prior to the passage thereof into said burner tubes, and means for automatically controlling the supply of fuel to the sections of said 85 burner.

15. A burner of the class described comprising a plurality of independent and substantially similar tubular sections in communication one with the other, burner tubes in juxtaposition to and beneath said sections and in communication therewith, a steam boiler associated with said sections and said burner tubes, a nozzle device in communication with said sections, said device being in communication with said steam generator and with a fuel oil supply, means whereby steam from said generator will control the feed of oil into said sections through said nozzle device, said steam and fuel being circulated through said sections to form thereof a combustible gas adapted 100 to be discharged from the tubes of said burner, and means whereby air may be entrained into said gas in its passage from said sections to said burner tubes.

16. A burner of the class described comprising a plurality of substantially similar tubular sections in communication one with the other, burner tubes in juxtaposition to and beneath said sections and in communication therewith, a steam boiler associated with said sections and said burner tubes, a nozzle device in communication with said sections, said device being in communication with said steam generator and with a fuel oil supply, means whereby steam from said generator will control the feed of oil into said sections through said nozzle device, said steam and fuel being circulated 105 110 115 120 125 130

through said sections to form thereof a combustible gas adapted to be discharged from the tubes of said burner, means whereby air may be entrained into said gas in its passage from said sections to said burner tubes, and means for automatically maintaining a constant water level in said generator.

17. A burner of the class described comprising a plurality of substantially similar tubular sections in communication one with the other, burner tubes in juxtaposition to and beneath said sections and in communication therewith, a steam boiler associated with said sections and said burner tubes, a nozzle device in communication with said sections, said device being in communication with said steam generator and with a fuel oil supply, means whereby steam from said generator will control the feed of oil into said sections through said nozzle device, said steam and fuel being circulated through said sections to form thereof a combustible gas adapted to be discharged from the tubes of said burner, means whereby air may be entrained into said gas in its passage from said sections to said burner tubes, means for automatically maintaining a constant water level in said generator, and means in communication with said generator for automatically controlling the supply of fuel to the nozzle device.

18. A burner of the class described comprising a plurality of substantially similar tubular sections in communication one with the other, burner tubes in juxtaposition to and beneath said sections and in communication therewith, a steam boiler associated with said sections and said burner tubes, a nozzle device in communication with said sections, said device being in communication with said steam generator and with a fuel oil supply, means whereby steam from said generator will control the feed of oil into said sections through said nozzle device, said steam and fuel being circulated through said sections to form thereof a combustible gas adapted to be discharged from the tubes of said burner, means whereby air may be entrained into said gas in its passage from said sections to said burner tubes, means for automatically maintaining a constant water level in said generator, and means for initially heating said steam boiler to generate steam in starting the burner operation.

19. A burner of the class described comprising a plurality of substantially similar tubular sections in communication one with the other, burner tubes in juxtaposition to and beneath said sections and in communication therewith, a steam boiler associated with said sections and said burner tubes, a nozzle device in communication with said

sections, said device being in communication with said steam generator and with a fuel oil supply, means whereby steam from said generator will control the feed of oil into said sections through said nozzle device, said steam and fuel being circulated through said sections to form thereof a combustible gas adapted to be discharged from the tubes of said burner, means whereby air may be entrained into said gas in its passage from said sections to said burner tubes, means for automatically maintaining a constant water level in said generator, means in communication with said generator for automatically controlling the supply of fuel to the nozzle device, means for initially heating said steam boiler to generate steam in starting the burner operation, and an adjustable valve for regulating the feed of oil to the automatic means and said nozzle.

20. A burner of the class described comprising a plurality of substantially U-shaped tubular sections mounted side by side, means for coupling said sections together and for placing the chambers thereof in communication to form a continuous coil from one end of the burner to the other, a fuel nozzle in communication with one of the end sections of the burner, burner tubes in communication with the other end section whereby fuel from said nozzle passes through said sections prior to its discharge through the burner tubes, a steam boiler mounted longitudinally of and within said sections, and means for placing said steam boiler in communication with said fuel nozzle whereby the steam generated by said boiler will control the entrainment of fuel into said sections and whereby said fuel and steam will be converted into a combustible gas in its passage through said sections.

21. A burner of the class described comprising a plurality of substantially U-shaped tubular sections mounted side by side, means for coupling said sections together and for placing the chambers thereof in communication to form a continuous coil from one end of the burner to the other, a fuel nozzle in communication with one of the end sections of the burner, burner tubes in communication with the other end section whereby fuel from said nozzle passes through said sections prior to its discharge through the burner tubes, a steam boiler mounted longitudinally of and within said sections, means for placing said steam boiler in communication with said fuel nozzle whereby the steam generated by said boiler will control the entrainment of fuel into said sections and whereby said fuel and steam will be converted into a combustible gas in its passage through said sections, and air admission means between the discharge of said sections and said burner tubes.

22. A burner of the class described com-

prising a plurality of substantially **U**-shaped tubular sections mounted side by side, means for coupling said sections together and for placing the chambers thereof in communication to form a continuous coil from one end of the burner to the other, a fuel nozzle in communication with one of the end sections of the burner, burner tubes in communication with the other end section whereby fuel from said nozzle passes through said sections prior to its discharge through the burner tubes, a steam boiler mounted longitudinally of and within said sections, means for placing said steam boiler in communication with said fuel nozzle whereby the steam generated by said boiler will control the entrainment of fuel into said sections and whereby said fuel and steam will be converted into a combustible gas in its passage through said sections, air admission means between the discharge of said sections and said burner tubes, and a gas burner tube mounted in said sections and beneath said steam boiler by means of which steam may be initially generated.

23. A burner of the class described comprising a plurality of substantially **U**-shaped tubular sections mounted side by side, means for coupling said sections together and for placing the chambers thereof in communication to form a continuous coil from one end of the burner to the other, a fuel nozzle in communication with one of the end sections of the burner, burner tubes in communication with the other end section whereby fuel from said nozzle passes through said sections prior to its discharge through the burner tubes, a steam boiler mounted longitudinally of and within said sections, means for placing said steam boiler in communication with said fuel nozzle whereby the steam generated by said boiler will control the entrainment of fuel into said sections and whereby said fuel and steam will be converted into a combustible gas in its passage through said sections, air admission means between the discharge of said sections and said burner tubes, gas burner tubes mounted in said sections and beneath said boiler by means of which steam may be initially generated, and means for automatically maintaining a fixed water level in said boiler.

24. A burner of the class described comprising a plurality of substantially **U**-shaped tubular sections mounted side by side, means for coupling said sections together and for placing the chambers thereof in communication to form a continuous coil from one end of the burner to the other, a fuel nozzle in communication with one of the end sections of the burner, burner tubes in communication with the other end section whereby fuel from said nozzle passes through said sections prior to its discharge

through the burner tubes, a steam boiler mounted longitudinally of and within said sections, means for placing said steam boiler in communication with said fuel nozzle whereby the steam generated by said boiler will control the entrainment of fuel into said sections and whereby said fuel and steam will be converted into a combustible gas in its passage through said sections, air admission means between the discharge of said sections and said burner tubes, gas burner tubes mounted in said sections and beneath said boiler by means of which steam may be initially generated, means for automatically maintaining a fixed water level in said boiler, and an automatic valve for controlling the supply of fuel to said nozzle device.

25. A burner of the class described comprising a plurality of substantially **U**-shaped tubular sections mounted side by side, means for coupling said sections together and for placing the chambers thereof in communication to form a continuous coil from one end of the burner to the other, a fuel nozzle in communication with one of the end sections of the burner, burner tubes in communication with the other end section whereby fuel from said nozzle passes through said sections prior to its discharge through the burner tubes, a steam boiler mounted longitudinally of and within said sections, means for placing said steam boiler in communication with said fuel nozzle whereby the steam generated by said boiler will control the entrainment of fuel into said sections and whereby said fuel and steam will be converted into a combustible gas in its passage through said sections, air admission means between the discharge of said sections and said burner tubes, gas burner tubes mounted in said sections and beneath said boiler by means of which steam may be initially generated, means for automatically maintaining a fixed water level in said boiler, an automatic valve for controlling the supply of fuel to said nozzle device, said valve being in communication with the steam boiler.

26. A burner of the class described comprising a plurality of independent and substantially **U**-shaped tubular sections, the crossheads of which forming an overlying dome for the burner, and the end portions of said tubular sections extending downwardly and inwardly beneath the dome of said sections, means for coupling the free end portions of said sections together and for placing the chambers thereof in communication to form a continuous coil of said sections from one end of the burner to the other, and burner tubes beneath said tubular sections and in communication therewith at one end of the coil formed by said sections.

27. A burner of the class described comprising a plurality of independent and sub-

- stantially **U**-shaped tubular sections, the crosshead of which forming an overlying dome for the burner, and the end portions of said tubular sections extending downwardly and inwardly beneath the dome of said sections, means for coupling the free end portions of said sections together and for placing the chambers thereof in communication to form a continuous coil of said sections from one end of the burner to the other, burner tubes beneath said tubular sections and in communication therewith at one end of the coil formed by said sections, a boiler mounted within the dome portion and end portions of said sections and above said burner tubes, and the arrangement of said burner tubes being such as to distribute the heat rising therefrom when the burner is in operation over the entire area of the coil formed by said tubular sections and said boiler. 30
- 5 29. A burner of the class described comprising a plurality of tubular sections in communication one with the other, burner tubes in juxtaposition to and beneath said sections and in communication therewith, and means for passing steam and fuel oil 40 into and through the sections of said burner to form thereof a combustible gas and for directing said gas to said burner tubes, and means for mingling air with the gas prior to the passage thereof into said burner tubes. 45
- 10 28. A burner of the class described comprising a plurality of independent and substantially **U**-shaped tubular sections, the crosshead of which forming an overlying dome for the burner, and the end portions of said tubular sections extending downwardly and inwardly beneath the dome of said sections, means for coupling the free end portions of said sections together and for placing the chambers thereof in communication to form a continuous coil of said sections from one end of the burner to the other, burner tubes beneath said tubular sections and in communication therewith at one end of the coil formed by said sections, a boiler mounted within the dome portion and end portions of said sections and above said burner tubes. 50
